LOOSE NAILING MACHINE

Charles A. Robinson, Salem, Mass., assignor to
United Shoe Machinery Corporation, Borough
of Flemington, N. J., a corporation of New
Jersey

Application July 20, 1940, Serial No. 346,589

7 Claims. (Cl. 1-18)

This invention relates to "loose nailing machines" and is illustrated as embodied in an improved nail separator.

In machines of the general type disclosed, for example, in United States Letters Patent No. 1,030,775, granted June 25, 1912, on an application filed in the name of George Goddu, there is disclosed a nail separator having an upper finger which during the initial forward movement of the separator isolates an endmost nail in a raceway and forces the head of the nail with considerable pressure against a nail driver operative in a channel of a driver guide, and which simultaneously therewith tips the lower end of the nail into the channel.

In order to insure that in the limited time available the head of the nail shall be forced into the channel of the driver guide and beneath the driver after said driver has been raised above the head of the nail and the separator has imparted to it a secondary forward movement, it has been found that the pressure which must be exerted against said nail by the upper finger is so great that the upper finger is unduly flexed and is frequently broken. Moreover, the pressure of the nail against the driver causes the latter to become burred, with the result that as the driver is raised out of contact with the nail it tends to lift the nail in the raceway and thus interferes with the proper insertion of the nail into the channel of the driver guide.

It is an object of the present invention to provide a loose nailing machine having an improved separator which will quickly and effectively deliver nails from a raceway into a channel of a driver guide without danger of breaking the separator or roughing up the driver as above described and thus interfering with the operation of the machine.

With the above object in view and in accordance with a feature of the present invention there is provided a loose nailing machine comprising a driver guide having a channel, a raceway for conducting a line of nails to said channel, a separator for isolating the endmost nail in the raceway from the remaining nails and delivering it to the channel, said separator having upper and lower fingers, the lower finger being constructed and arranged to be held positively against the driver guide during a portion of the operation of the machine and the upper finger being mounted for yielding movement relatively to the lower finger away from the driver guide, and resilient means for constantly urging the upper finger toward the driver guide.

In the illustrative machine the upper finger of the separator has a hook-shaped portion constructed and arranged to be loosely received in a channel of the lower finger of the separator. 5 The upper finger is normally held in the general plane of the lower finger by a spring-pressed plunger housed in an arm through which the separator is yieldingly operated in a rectilinear path disposed transversely of the raceway. When the separator is initially moved between the first and second nails in the raceway, it swings the lower end of the first nail into the channel of the driver guide and also forces the head of said nail against the driver in said guide and 10 at the same time yields slightly against action of the spring-pressed plunger with relation to the lower finger and away from the driver guide, thereby insuring that the head of the nail shall not be forced with excessive pressure against the driver and thus insuring against breakage 15 of the upper finger, the lower finger of the separator in the meantime assisting, if necessary, to cause the lower end of the nail to be swung into the channel of the driver guide. As the 20 driver is raised above said first nail in the raceway the separator is moved further forward between the first and second nails and is swung toward the driver guide by the spring-pressed plunger, thereby flipping the head of the nail 25 into the channel of the driver guide and beneath the driver. During the second step forward of the separator a flat face of the lower finger closes up the open side of the channel of the driver guide and forms therewith a closed or 30 unbroken passageway which serves as a guide for the driver and through which the nail is delivered to a cylindrical passageway of a throat 35 into which the nail is fed from the channel of the driver guide preparatory to driving the nail 40 into the work.

By providing a separator the upper finger of which is yieldable away from the driver guide with relation of the lower finger it is possible quickly and effectively to deliver nails to the nail 45 driving mechanism of the machine without danger of breaking the separator, the pressure of the upper finger against the nail never being great enough to cause the nail to rough up the driver as above described. Moreover, by having 50 the lower finger held against movement away from the driver guide during the driving of the nail, said lower finger, in combination with the driver guide, forms an effective passageway for controlling movement of the driver, it being 55 appreciated that if the lower finger of the sep-

arator were yieldable away from the driver guide and the driver were slightly sprung, as is sometimes the case, said driver would not be properly guided into the cylindrical passageway of the throat.

The various features of the invention will be understood and appreciated from the following detailed description read in connection with the accompanying drawings, in which

Figs. 1 and 2 are perspective views, partly broken away and partly in section, showing the operating head of the illustrative loose nailing machine during two different stages in the operation of the machine;

Fig. 3 is a section, partly broken away, on line III—III of Fig. 4;

Figs. 4 to 7, inclusive, are sectional views, partly broken away, on line IV—IV of Fig. 1, showing the different operative parts of the machine during four different stages in the operation of the machine; and

Figs. 8 and 9 are perspective views of a nail separator of the illustrative machine.

As in the machine disclosed in said Letters Patent No. 1,030,775, the illustrative machine comprises an abutment 20, a horn 22 for supporting a shoe 24 the sole 26 of which is to be attached by nails 27, and for forcing said sole against the abutment 20, a gage 28 (Fig. 3) shaped and arranged to be engaged by the edge of the sole, a nail driver 30 which is secured to a slide 32 (Figs. 1 and 2) mounted for vertical movement in a guideway 34 (Fig. 1) of the frame 36 of the machine, and a driver guide 38 which is secured to the machine frame and has a channel 40 in which the driver 30 reciprocates.

Preparatory to driving each nail 27 a hole 42 (Figs. 6 and 7) is punched in the sole 26 of the shoe by an awl 44 which, after punching said hole, feeds the shoe in engagement with the gage 28 from its position shown in Fig. 4 to its position shown in Fig. 5, the arrangement being such that the hole is moved to a position directly beneath the driver 30 and into alignment with a cylindrical passage 46 (Figs. 4, 6 and 7) of a throat 48 moved to its operative position shown in Figs. 6 and 7.

The nails 27 are fed to the channel 40 of the driver guide 38 along a raceway 50 the lower end of which is approximately in contact with a face 52 (Figs. 1 and 2) of the driver guide 38, a nail slot 54 (Fig. 1) of the raceway being arranged opposite the channel 40. The nails are arranged in alignment in the nail slot 54 of the raceway 50 and are fed one by one to the channel 40 of the driver guide 38 by an improved separator 56 (Figs. 8 and 9) to which this application is mainly directed, and which, as will appear later, advances across the line of nails 27 in the raceway 50 to separate or isolate the endmost nail in the raceway from the remaining nails and later to inject the endmost nail into the channel 40 of the driver guide 38.

The throat 48 has a tongue 58 (Figs. 4, 5, 6 and 7) fitting in a groove 60 of a carrier slide 62 and is secured to the slide by a clamp screw 64. In order to move the throat 48 from its operative or forward position shown in Figs. 1, 3, 4, 6 and 7 to its retracted or rearward position shown in Figs. 2 and 5 in order to allow the awl 44 after penetrating the sole to feed the same so that the punched hole 42 will be located directly beneath the throat after the same has been moved into its operative position, the carrier slide 62 is movable along a rectilinear guide-

way 66 (Fig. 3) of the machine frame through the provisions of a rack 68 which meshes with a pivotally mounted segment gear 70 having at its upper end a cam roll (not shown).

Supported upon the carrier slide 62 is the separator 56 (Figs. 8 and 9) which, as will appear later, may yield relatively to the carrier slide should the separator during its forward stroke hit a nail 27 in the raceway 50 on dead center, for example. The connecting mechanism between the separator 56 and the carrier slide 62 comprises a cylindrical slide 72 (Figs. 1, 2 and 3) having at its enlarged forward end a groove 74 in which fits a tongue 76 of a bracket 78, the arrangement being such that the bracket may be initially secured by a screw 80 in its proper adjusted position to the carrier slide, so as to insure that the separator may effectively engage the face 52 of the driver guide 38 in order to close the open side of the channel 40, as will appear later. The cylindrical slide 72 is guided in a cylindrical guideway 82 of the machine frame and has housed within it a spring 84 (Fig. 3) the forward end of which engages the cylindrical slide and the rear end of which engages the rear end of a recess 86 of a slide 88 housed within the cylindrical slide. Formed in the cylindrical slide 72 is a recess 90 in which fits a lug 92 extending upwardly from the carrier slide, the cylindrical slide 72 being provided with a slot 94 so that the separator can yield with relation to the carrier slide as above described should said separator, for example, hit the center of a nail in the raceway, the spring 84, which is relatively strong, in the normal operation of the machine serving to force the rear end of the slot 94 against the lug 92, as illustrated in Fig. 3.

As will appear later, the separator comprises upper and lower fingers 96 and 98, respectively, the lower finger being provided with a tongue 100 (Figs. 2 and 8) fitting in a groove 102 of the bracket 78 and being secured to the bracket by a screw 104 which passes through a cylindrical recess in the bracket and is threaded into the lower finger.

In order to eliminate the breakage of the upper fingers of one-piece separators such as disclosed in said Letters Patent No. 1,030,775, and to insure that the driver 30 shall not be burred or otherwise roughed up by the nails 27 fed through the machine, and thus interfere with the proper insertion of said nails into the channel 40 of the driver guide 38, the upper finger 96 of the separator 56 is mounted for tilting movement upon the lower finger 98 of the separator which is similar to the lower finger of the separator shown in said Letters Patent. Formed in the lower finger 98 of the separator is a groove 105 (Figs. 8 and 9) shaped and arranged loosely to receive a hooked portion 106 of the upper finger 96, the arrangement being such that the upper finger is normally held by a spring-pressed plunger 108 (Fig. 8) in the general plane of the lower finger, flat faces 110 (Fig. 9) and 112, respectively, of the upper and lower fingers normally being in approximate alignment. The spring-pressed plunger 108 (Fig. 8) is housed in a recess 114 of the bracket 78, the effective strength of a spring 116 backing up the plunger being varied by turning a screw 118 threaded in the recess.

When the machine is idle, the separator 56 is interposed between the driver 30 and the endmost nail 27 in the raceway 50, the driver being down and the awl 44 up. When the machine is started, the driver 30 is raised to clear the throat

48, the awl 44 being lowered to its position shown in Fig. 4, causing it to penetrate the sole 26, the awl then moving to the left to its position shown in Fig. 5 to move the hole 42 formed in the sole 26 of the shoe 24 directly in alignment with the driver 30. As the sole of the shoe is being fed by the awl 44 the carrier slide 62 is moved rearwardly and moves with it the throat 48 and the separator 56, there being a slight dwell in the upward movement of the driver 30 after it has cleared the throat 48, as shown in Fig. 5, so as to cause the driver to block the end of the nail slot 54 of the raceway 50 and thus prevent any part of the endmost nail in the raceway from entering the channel 40 of the driver guide 38. While the awl 44 is being withdrawn from the sole 26 of the shoe 24 the driver 30 is moved upwardly until its lower end is arranged opposite the head of said endmost nail, at which time the driver 30 has a second dwell, the separator 56 during this period moving forwardly and transversely of the raceway 50 between the first two 10 nails in the raceway, the thin leading portion 120 (Figs. 8 and 9) of the upper finger 96 entering beneath the shanks of the nails just below their heads, an upwardly beveled face 122 (Fig. 9) of said finger then tipping the pointed or lower end of the nail into the channel 40 of the driver guide 38 while the head of the nail is forced against the driver, as illustrated in Fig. 6.

The nail 27 is usually swung into the channel 40 of the driver guide 38, as above described, by the action of the upper finger 96 alone. It sometimes happens, however, that when the nail is bent, for example, the lower end of the same is not properly turned into the channel 40 by the upper finger 96, in which case a beveled face 124 (Fig. 9) of the lower finger 98 forces the nail into the channel. After the lower end of the nail has been tipped into the channel 40 of the driver guide 38, the face 112 of the separator which engages the face 52 of the driver guide 38 covers the channel and forms therewith an unbroken passageway through which the nail may be effectively delivered to the passageway 46 of the throat 48 and which serves positively to guide the driver 30 to said passageway 46.

After the lower end of the nail 27 has been swung into the channel 40 of the driver guide 38, as above described, there is a slight dwell in the forward movement of the separator 56 and the throat 48, during which the driver 30 moves upwardly and releases the head of the nail. Immediately upon the release of the nail the separator 56 and the throat 48 have imparted to them a secondary forward movement, the face 110 of the upper finger 96 camming the head of the nail into the channel 40 just before the driver 30 descends to drive said nail. In the normal operation of the machine the descending driver 30 engages the head of the nail before it has time to drop by gravity through the passageway formed by the channel 40 of the driver guide 38 and the face 112 of the lower finger 98, and drives the nail through the sole of the shoe and against the horn 22, thereby clenching said nail.

It will be noted that the machine runs at a speed of approximately 550 or more cycles per minute and that the interval between the time that the nail is released and the driver comes down against said nail is extremely short. As above stated, in loose nailing machines of the type described in said Letters Patent No. 1,030,775, having a separator the upper and lower fingers of which are made of one piece, it has been found

that, in order for the upper finger of the separator to move the head of the nail into the channel of the driver guide before the driver moves downwardly against the nail, it is desirable, during the initial forward movement of the separator, to force said upper finger against the head of the nail with so much force that it flexes said finger away from the driver guide. When the nail is released, it will be appreciated that the upper finger is flipped back toward the driver guide and that such movement of the finger in combination with the secondary forward camming movement of the same causes the head of the nail, which has a tendency to hang on the raceway, to be moved into the channel within the short time required. As above explained, it frequently happens that the pressure of a slightly bent or otherwise poorly formed nail frequently causes the upper finger of the one-piece separator, during its initial forward movement, to be excessively flexed away from the driver guide, with the result that the finger is fractured. Moreover, it has been found that when a one-piece separator is used, the nail has to be forced against the driver with so much force that it burrs the driver and, accordingly, such driver tends to pick the nail from the raceway at the critical time that said nail is to be moved into the channel of the driver guide, thereby interfering with the proper operation of the machine.

By providing the separator 56 with a separately formed upper finger 96 which is mounted for tilting movement away from the driver guide 38, and backing up said upper finger by the spring 116, it will be clear that said finger is deflected slightly away from the driver guide 38 to its dotted line position, for example, shown in Fig. 9, against the action of the spring-pressed plunger 108 during the initial forward movement of the separator. As the driver 30 releases the head of the nail and the separator 56 has said secondary forward movement imparted to it, the upper finger 96 is moved or flipped back against the face 52 of the driver guide 38 by the spring-pressed plunger 108, the joint effect of the swinging action and the forward camming action of the upper finger being quickly and effectively to move the head of the nail into the channel 40 of the driver guide 38 and beneath the driver 30. Whenever there is a poorly formed nail at the lower end of the groove 54 of the raceway 50, the upper finger 96 of the separator 56 yields away from the driver guide 38 sufficiently to insure against breakage of the separator. By providing the illustrative separator it has been found that the above-mentioned burring of the driver 30 has been eliminated, thereby insuring against the nail being raised on the raceway 50 by the driver just as it is about to be inserted into the channel 40 of the driver guide 38.

It will be noted that after the lower end of the endmost nail 27 has been swung into the channel 40 of the driver guide 38, the face 112 of the lower finger 98 of the separator 56 is moved forwardly into engagement with the face 52 of the driver guide 38, causing the lower finger to form with the driver guide an unbroken passageway. Since the lower finger 98 of the separator 56 is held against yielding movement away from the face 52 of the driver guide 38, a rigid passageway for the nail and the driver is formed by the driver guide and the lower finger of the separator.

Should the lower finger 98 of the separator 56 be yieldable away from the face 52 of the driver

guide 38, the operation of the machine would be seriously interfered with, since a nail with a defective head, for example, when being driven might then force the lower finger of the separator away from the driver guide with the result that the nail would not be properly guided into the passageway 46 of the throat 48. Moreover, it has been found that the driver frequently becomes sprung, and unless there is a rigid passageway for guiding the driver 30, said passageway will not effectively guide the driver into the passageway of the throat.

Having described my invention, what I claim as new and desire to secure by Letters Patent of the United States is:

1. A loose nailing machine having, in combination, a driver guide having a channel, a raceway for conducting a line of nails to said channel, a separator for isolating the endmost nail in the raceway and delivering said nail to the channel, said separator comprising separate upper and lower fingers, the lower finger being positively held in engagement with the driver guide during a portion of the operation of the machine and the upper finger being movable relatively to the lower finger and away from the driver guide, and yieldable means for constantly urging the upper finger toward the driver guide.

2. In a loose nailing machine, a nail separator comprising a lower finger having a flat face, an upper finger which has a flat face and is mounted for movement with relation to the lower finger, and means comprising yieldable mechanism constructed and arranged normally to maintain said face of the upper finger in the general plane of the face of the lower finger but to permit said face of the upper finger to move out of the general plane of the face of the lower finger.

3. In a loose nailing machine, a driver, a guide for the driver, said guide having a channel, a raceway for feeding a line of nails to said channel, a nail separator movable across the line of nails in the raceway to isolate the endmost nail and to deliver said nail to said channel, said separator comprising a lower finger, an upper finger which is movable generally lengthwise of the line of nails with relation to said lower finger, and resilient means constructed and arranged normally to maintain the upper finger in a general plane of the lower finger but to permit the upper finger to move away from the driver guide and out of said general plane of the lower finger.

4. A loose nailing machine having, in combination, a driver guide having a channel, a raceway for feeding a line of nails to said channel, a yieldable presser member, and a separator movable across the line of nails to isolate the endmost nail in the raceway and to deliver said endmost nail to the channel, said separator comprising a lower finger having a face constructed and arranged during a portion of the cycle of operation of the machine to be positively held against the driver guide to close an open side of said channel, said separator also comprising an upper finger which is mounted for bodily movement away from the driver guide against the action of said presser member during a portion

of the movement of the separator across the line of nails, the upper finger being bodily moved toward the driver guide by said presser member during another portion of the movement of the separator across said line of nails.

5. A loose nailing machine having, in combination, a driver, a guide for the driver, said guide having a channel for receiving said driver, a raceway for feeding a line of nails to said channel, a separator yieldingly movable across the line of nails to isolate the endmost nail in the raceway from the remaining nails and to cause said endmost nail to be transferred into said channel, said separator comprising upper and lower fingers, and means for normally maintaining faces respectively of the fingers in the same general plane and for permitting the upper but not the lower finger to yield away from the driver guide during the movement of the separator across the line of nails.

6. A loose nailing machine having, in combination, a driver, a guide having a channel for receiving the driver, a raceway constructed and arranged to feed a line of nails to said channel, a separator, and operating mechanism for said separator constructed and arranged to advance the separator across the line of nails to separate the endmost nail from the line of nails in the raceway and to move the endmost nail so separated into the channel, said separator comprising a pair of fingers one of which is nonyieldable lengthwise of the line of nails and is constructed and arranged to cover a portion of the channel of the driver guide and the other of which is yieldable away from the driver guide lengthwise of the line of nails.

7. A loose nailing machine having, in combination, a driver, means for operating the driver, a driver guide having a channel, a throat having a passageway, a raceway constructed and arranged to feed a line of nails to the channel of the driver guide, a nail separator, mechanism for advancing the separator with yielding pressure across the line of nails to separate the endmost nail from said line of nails, said separator comprising upper and lower fingers, said upper finger being constructed and arranged to force the head of said endmost nail against the driver and the lower end of the nail into the channel during movement of the separator across the line of nails, and means comprising a spring actuated member for enabling said upper finger to yield away from the driver guide during a portion of the movement of the separator to insure against forcing the head of the nail with excessive pressure against the driver, said spring actuated member being constructed and arranged to cause said upper finger to force the head of the nail into said channel when the driver is moved away from the nail during another portion of the operation of the machine, the lower finger of the separator being constructed and arranged to close an open side of the channel in the driver guide and being nonyieldable away from the driver guide in order to insure that the channel shall serve as a positive guideway for the driver.

CHARLES A. ROBINSON.
